UNITED STATES PATENT OFFICE.

CHESLEY T. SMALL, OF ST. LOUIS, MISSOURI.

CAN-BRUSHING MACHINE.

1,312,589.

Specification of Letters Patent.

Patented Aug. 12, 1919.

Application filed May 8, 1918. Serial No. 233,237.

To all whom it may concern:

Be it known that I, CHESLEY T. SMALL, a citizen of the United States of America, residing at the city of St. Louis, State of Missouri, United States of America, have invented a certain new and useful Can-Brushing Machine, of which the following is such a full, clear, and exact description as will enable any one skilled in the art to 10 which it appertains to make and use the same, reference being had to the accompanying drawings, forming part of this specification.

My invention relates to a can brushing machine, and more particularly to one which is adapted to be applied to the conveyer of a can filling machine.

In the accompanying drawings, which illustrate one form of can brushing machine made in accordance with my invention, together with a portion of the conveyer of a can filling machine to which the same is applied, Figure 1 is a top plan view, partly in section; Fig. 2 is a side view; 25 Fig. 3 is an enlarged section taken on the line 3—3 of Fig. 1; Fig. 4 is a diagram illustrating the action of the brushes; and Fig. 5 is an enlarged section taken on the line 5—5 of Fig. 3.

10 indicates the T-rails of the conveyer of a can filling machine. These T-rails 10 are provided with slots in which travel chains 11, the cans being carried upon the upper surfaces of said chains. Passing through the 35 T-rails 10 are rods 12, upon which are carried brackets 13, supporting a guide-rail 14, for guiding the cans traveling upon the chains 11. All of the above described parts are like those shown and described in my 40 prior application for patent for a can filling machine, Serial No. 184,990, filed August 11, 1917, and form no part of the present invention, except in combination with the parts hereinafter to be described.

15 are side frames, each of which is provided with a pair of hubs 16, passing around the cross rods 12, hereinbefore described. The frames can be adjusted toward and away from the conveyer, and are held in 50 position by means of set screws 17. 18 are vertical spindles carried in roller bearings 19 (Figs. 3 and 5) which bearings are contained in brackets 20, secured to the said frames 15. The number of spindles 18 may 55 be varied to meet the requirements of the machine. In the drawings I have shown

a set of three spindles, as carried by each of the side frames 15. Mounted on each of the spindles 18 are a number of brush members 21, each of which is provided with one or more annular rows of bristle tufts 22. The brush members 21 are secured to the spindles 18 by means of set screws 23, as shown in Fig. 3 of the drawings. By loosening the set screws 23 some of the brush members 21 may be removed, or more brush members may be added, so as to adapt the machine to cans of varying heights. These set screws 23 also permit the brush member 21 to be relatively adjusted around the spindles 18, so that the vertical rows of bristle tufts 22 may be brought into alinement, as shown in Fig. 2 of the drawings, or the tufts of the various brush members may be staggered or otherwise relatively placed so as to 75 secure the best results upon the particular kind of cans upon which the machine is to operate.

In order to avoid any interference with the action of the bristles upon the cans 80 throughout their entire length, I remove a portion of each of the guide rails 14 adjacent to the frames 15 and secure across the spaces thus formed a thin guide rail 24, which is adapted to pass between two of the annular rows of bristle tufts without 85 interfering with the action of the brushes, as best shown in Fig. 3 of the drawings. In order to rotate the spindles 18 I provide each of said spindles with a pulley 25. Two of the spindles are also provided with a second pulley 26. The pulleys 25 of the middle and last spindle 18 are surrounded by a belt 27, while the pulleys 26 of the middle and first spindle are surrounded by a 90 similar belt 28. The pulleys 25 of the first spindles are driven by means of belts 29 which pass around pulleys 30 upon a cross shaft 31, upon which is mounted a driving pulley 32, by means of which the machine is 95 driven from any suitable source of power. As the spindles 18 are vertical and the shaft 31 is horizontal, the belts 29 are quartered, and this together with the fact that it is desirable to adjust the frames 15 toward and 100 away from the conveyer without disturbing the pulleys 30, requires the use of a round flexible belt for driving the pulleys 25. In order to secure this result I form the belt 29 of a coil of spring wire. The belts 27 and 28 may also be formed of similar coils 110 of spring wire, this, however, is not essen-

tial, and any ordinary form of belting may be used for these belts 27 and 28.

The individual bristle tufts 22 of each annular row are arranged in juxtaposition around the periphery of the brush members 21, but are normally out of contact, as shown in Fig. 1 of the drawings, and diagrammatically in Fig. 4. The belts 29 are so arranged as to drive the brush members 21 in the same direction as indicated by the arrows A in Fig. 4. The action of the bristle tufts 22 upon the cans 33 is such as to rotate them in the direction indicated by the arrow B of said figure as the said cans are carried forward in the direction indicated by the arrows C on the conveyer chains 11. This rotation of the cans between the brushes allows the cans to be acted on throughout their entire periphery, thus removing all the dust and particles of powder which adhere to the cans after coming from the filling machine. The individual bristle tufts 22 when brought into contact with the periphery of the cans are bent back, as indicated at D. After moving out of contact with the surfaces of the can each bristle tuft springs forward and strikes with considerable force against the preceding tuft, as indicated at E. This action frees the bristle tufts of the adhering particles of dust or powder.

Having fully described my invention, what I claim as new and desire to secure by Letters Patent of the United States is:

1. In a can brushing machine, the combination with a traveling conveyer for the cans, guiding means for positioning the cans on said conveyer, of a pair of brushes, one situated at each side of the conveyer, means for independently adjusting each of said brushes toward and away from said conveyer, and means for rotating said brushes in the same direction, whereby the cans are rotated on the conveyer as they pass between said brushes.

2. In a can brushing machine, the combination with a traveling conveyer for the cans, of a pair of vertical spindles, one situated at each side of the conveyer, each of said spindles having mounted thereon brushes comprising a plurality of removable

brush members, whereby the machine may be adapted to cans of varying heights, and means for rotating said brushes in the same direction, whereby the cans are rotated on the conveyer as they pass between said brushes.

3. In a can brushing machine, the combination with a traveling conveyer for the cans, of a pair of vertical spindles, one situated at each side of said conveyer, each of said spindles having mounted thereon a brush comprising a plurality of members, means for relatively adjusting the brush members around their axis of rotation, and means for rotating said brushes in the same direction, whereby the cans are rotated on said conveyer as they pass between said brushes.

4. In a can brushing machine, the combination with a traveling conveyer for the cans, of a pair of frames, one arranged at each side of said conveyer, means for adjusting said frames toward and away from said conveyer, vertical spindles carried by said frames and provided with pulleys, brushes carried by said spindles, a driving shaft provided with pulleys, and elastic belts connecting the pulleys on said driving shaft with the pulley on a pair of said spindles.

5. In a can brushing machine, the combination with a rail forming a support for a traveling conveyer, of a pair of cross rods carried by said rail, a pair of guide rails supported from said cross rods, a pair of frames supported on said cross rods and provided with rotary brushes, and means for driving said brushes.

6. In a can brushing machine, the combination with a rail supporting a traveling conveyer, of a pair of cross rods carried by said rail, guide rails supported from said cross rods, frames adjustably carried by said cross rods, vertical spindles carried by said frames and provided with rotary brushes, and means for rotating said spindles.

In testimony whereof, I have hereunto set my hand and affixed my seal.

CHESLEY T. SMALL. [L. S.]
